UNITED STATES PATENT OFFICE

MARY E. TOWLER, OF LAMPASAS, TEXAS

CAP FOR AUTOMOBILE RADIATORS

Application filed October 1, 1928. Serial No. 309,419.

This invention relates to an improved cap for the radiators of automobile engines.

One object of the invention is to provide a radiator cap having vent tubes to coat with the overflow pipe of a radiator for providing a circulation of air above the body of water in said radiator.

Another object of the invention is to provide a radiator cap wherein the vent tubes will retard the movement of boiling water through said tubes to prevent a waste of the water.

A further object of the invention is to provide a radiator cap wherein the vent tubes will provide handles for facilitating the removal of the cap from the filler neck of the radiator.

And a still further object of the invention is to provide a radiator cap utilizing means for condensing vapors such as are freed from boiling water or anti-freeze solutions, so that the products of condensation will be permitted to flow back into the radiator.

Other objects of the invention not specifically mentioned in the foregoing will be apparent during the course of the following description.

In the accompanying drawings:

Figure 1 is a sectional view of the device showing it in position attached to the filler neck of a radiator,

Figure 2 is a top plan view of the device,

Figure 3 is a fragmentary sectional view showing a slight modification of the invention.

Referring more particularly to the drawings, the numeral 1 indicates the usual filler neck of an automobile radiator, and extending into said radiator and into the filler neck is a conventional overflow pipe 2, open at its lower end to the atmosphere.

Screwed into the filler neck is a substantially cylindrical shell 3 closed at its upper end by an end wall 4 and reduced at its lower end portion to form a shoulder 5 coacting with the upper edge of the filler neck to provide a sealed joint.

Formed on the upper end wall of the shell is a knob 6 to facilitate the removal of the cap from the filler neck of the radiator.

Formed on the peripheral wall of the shell are aligned oppositely disposed radial tubes 7 closed at their outer ends to provide water checks 8 and mounted in the same vertical plane with said tubes are oppositely presented substantially U-shaped tubes 9, said tubes being provided with short upper legs 10 and long lower legs 11 closed at their outer ends to provide water checks 12. Connecting the lower legs 11 of the U-shaped tubes with the inner end portions of the radial tubes 7 are tubes 13 tilted obliquely and presented in opposite directions, said tubes 13 having the upper ends integral with the legs 11 and the lower ends integral with the inner end portions of the radial tubes 7. The water checks 8 provide primary retarding means for water surging upwardly through the neck 1, and the water checks 12 provide secondary retarding means for the water. The bends of the U-shaped tubes provide a third retarding means for the water.

Due to the slight vacuum formed adjacent the outer ends of the short upper legs 10 of the U-shaped tubes when the automobile is in motion, said tubes will coat with the overflow pipe 2 to produce a draft of air in the radiator above the body of water carried therein to assist in keeping the water cool. The tubes also provide handles to facilitate the removal of the shell from the filler neck when it is desired to add more water. If steam should be generated in the radiator, it would pass out through the tubes, and if the water should boil and be caused to surge upwardly, it would be retarded by the checks and the bends of the U-shaped tubes, and would be caused to flow back into the radiator.

Referring more particularly to the modification of the invention, as shown in Figure 3 of the drawing, the numeral 14 indicates the outer end portion of the short leg of one of the U-shaped tubes. Removably screwed on said end is a cap 15 and overlying the inner end wall of said cap is a washer 16 for sealing the tube when so desired, particularly in winter. A similar cap is employed on the oppositely presented tube. Aside from the foregoing, the modification of the invention

tion is identical with the preferred form and functions in like manner.

Having thus described the invention, I claim:

5 A radiator cap including a shell, oppositely presented laterally disposed tubes extending from the shell, said tubes being closed at their ends to provide water checks, outwardly inclined tubes upstanding from said laterally disposed tubes near their inner ends, and oppositely presented U-shaped tubes having relatively short upper legs open at their ends and relatively long lower legs connected medially with said inclined tubes and closed 10 at their ends to provide water checks, all of said tubes cooperating to retard the upward flow of water from a radiator.

In testimony whereof I affix my signature.

MARY E. TOWLER. [L. s.]
